(57) **CLAIM**

The ornamental design for a license plate, as shown and described.

DESCRIPTION

FIG. 1 is a perspective view of my license plate;
FIG. 2 is a front elevational view of my license plate;
FIG. 3 is a rear elevational view of my license plate;
FIG. 4 is a left side elevational view of my license plate;
FIG. 5 is a right side elevational view of my license plate;
FIG. 6 is a top view of my license plate; and,
FIG. 7 is a bottom view of my license plate.
Shading lines in the various views are for illustrative purposes only and form no part of the design.
